UNITED STATES PATENT OFFICE.

EDWARD C. TEAGUE, OF KANSAS CITY, MISSOURI.

CLEVIS.

Application filed August 29, 1924. Serial No. 735,033.

To all whom it may concern:

Be it known that EDWARD C. TEAGUE, a citizen of the United States of America, residing at Kansas City, in the county of 5 Jackson and State of Missouri, has invented new and useful Improvements in Clevises, of which the following is a specification.

The purpose of the invention is to improve the construction of clevises so that the 10 coupling pin may be effectively latched in position on the yoke to complete its recession and yet be susceptible of manipulation to move it to open position, the device being applicable particularly to railroad use as a 15 means of coupling the uncoupling rod to the pin lift on the coupler, thus replacing the conventional form of clevis in which the coupling pin is retained in closed position by the application of a cotter pin or the 20 like which are frequently lost or sheared off, thus permitting the coupling pin of the clevis to recede.

With this general purpose in view, the invention consists in a construction and combination of parts of which a preferred embodiment is illustrated in the accompanying drawings, wherein:

Figure 1 is a side elevational view of a clevis embodying the invention.

Figure 2 is an edge view.

Figure 3 is a section on the line 3—3 of Figure 1.

Figure 4 is a section on the line 4—4 of Figure 1.

Figure 5 is a detail view of the coupling pin 4.

The yoke 1 is of the usual form with enlargements 2 at the extremities of the limbs of the yoke, the enlargements being transversely bored, as indicated at 3, for the reception of the coupling pin 4, the bores or eyes 3 being adjacent the point of juncture of the enlargements with the limbs to provide a large amount of stock behind the 45 eyes to add strength to the yoke in the vicinity of the eyes. The coupling pin is adapted for longitudinal movement in the eyes or bores 3 but is precluded from angular or turning movement, being provided with a longitudinal slot 5 into which projects a pin 6 carried by one of the limbs of the yoke and frictionally held in a hole bored in the latter.

When the coupling pin spans the limbs of 55 the yoke, the head 7 of the pin abuts one of the enlargements on the outer face. The

other of the enlargements is transversely slotted, as indicated at 8, to provide a recess for the head 9 of the latching pin 10, the latter projecting through a plate 11 seated 60 in the bottom of the recess and covering a cavity 12 in the enlargement. The latching pin is yieldingly impelled toward the coupling pin by a spring 14 surrounding the pin and compressed between the under face of 65 the plate and a small transverse pin 15 inserted diametrically through the latching pin. The coupling pin is provided with a transverse recess or notch 17 constituting a seat for the latching pin when the coupling 70 pin is in its closed position transversely spanning the limbs of the yoke.

The head 8 of the latch pin is provided with opposite flats 18 for grasping the head between the fingers so that the latching pin 75 may be retracted and the coupling pin thus withdrawn from latching position. The coupling pin is beveled off on the extremities, as indicated at 19, to enable it when the notched end is inserted in its respective 80 eye, to engage the latching pin and raise the latter until the coupling pin reaches a position wherein the latching pin may be repressed into the notch or seat 17. The transverse slot, as indicated at 8, at the end 85 of one of the enlargements of the yoke includes walls on opposite sides of the head of the latching pin and the recess caused to be formed by the walls is open at right angles to the walls to permit ready access of the 90 fingers of an operator whereby the head of the latching pin may be grasped for operating the same. The opposing walls act to protect the head, preventing contact of a foreign object with the head of the pin 95 which would tend to change the position of the head or cause it to disengage from the notch of the coupling pin or possibly break the head from the pin. It will be noted that the walls overlie the head sufficiently to protect the sides and ends of the head of the latching pin and yet permit the fingers of an operator to engage with the head of the pin.

The invention having been described, 105 what is claimed as new and useful is:

A clevis comprising a yoke of which the limbs are provided with eyes, a coupling pin 110 slidably engaged in said eyes and adapted for position in spanning relation with said limbs, one of said limbs being provided on its end with opposed projecting walls de-

fining an intervening recess open at its sides which are at right-angles to the walls, said limb having a cavity communicating with said recess, a plate fitted over and covering said cavity, and a latching pin mounted in said cavity below the plate and yieldingly impelled toward said coupling pin which is provided with a notch or seat for the latching pin, said latching pin having a finger

engaging head immediately beyond the plate and disposed between said projecting walls for engagement by the fingers of an operator for the purpose of retracting the latching pin. 10

In testimony whereof he affixes his signature. 15

EDWARD C. TEAGUE.
